(57) **CLAIM**

The ornamental design for a blot and gel imaging instrument display screen with graphical user interface, as shown and described.

DESCRIPTION

FIG. 1 is a front view of a blot and gel imaging instrument display screen with graphical user interface showing our new design;

FIG. 2 is a second embodiment thereof;

FIG. 3 is a third embodiment thereof; and,

FIG. 4 is a fourth embodiment thereof.

The broken lines showing the display screen and elements of the graphical user interface form no part of the claimed design.
